CLAIM

The ornamental design for a combined toy bus and figurines, as shown and described.

DESCRIPTION

FIG. 1 is a right side perspective view of a combined toy bus and figurines showing our new design;

FIG. 2 is a front elevational view thereof;

FIG. 3 is a rear elevational view thereof;

FIG. 4 is a top plan view thereof;

FIG. 5 is a bottom plan view thereof;

FIG. 6 is a cross-sectional view thereof taken substantially along the line 6—6 of FIG. 4; and

FIG. 7 is a left side elevational view thereof.

*Fig. 1**Fig. 2**Fig. 3*

*Fig. 4**Fig. 5**Fig. 6*
